US0D1063447S

(12) **United States Design Patent** (10) **Patent No.:** **US D1,063,447 S**
(45) **Date of Patent:** **** Feb. 25, 2025**

(54) **SHAPED PILLOW**

(71) Applicant: **Shengbiao Wu**, Ningbo (CN)

(72) Inventor: **Shengbiao Wu**, Ningbo (CN)

(**) Term: **15 Years**

(21) Appl. No.: **29/884,505**

(22) Filed: **Feb. 13, 2023**

(30) **Foreign Application Priority Data**

Nov. 7, 2022 (CN) 202230739261.0

(51) **LOC (15) Cl.** **06-09**

(52) **U.S. Cl.**

USPC **D6/601**
